Specification for Design.

Patented May 16, 1922.

Application filed July 26, 1921. Serial No. 487,721. Term of patent 3½ years.

To all whom it may concern:

Be it known that I, FRANK SCHOECK, a citizen of the United States, residing at 319 Rowland Street, Syracuse, in the county of Onondaga and State of New York, have invented a new, original, and ornamental Design for Sewing Cabinets, of which the following is a specification, references being had to the accompanying drawing, forming part thereof.

Figures 1 and 2 of the drawings are perspective views of a sewing cabinet closed and open, respectively, showing my new design.

I claim:

The ornamental design for a sewing cabinet as shown.

FRANK SCHOECK.
